UNITED STATES PATENT OFFICE.

ALFRED BONOM, OF PATERSON, NEW JERSEY.

STEAM-TURBINE.

1,076,810.

Specification of Letters Patent.

Patented Oct. 28, 1913.

Application filed January 24, 1913. Serial No. 743,960.

To all whom it may concern:

Be it known that I, ALFRED BONOM, a citizen of the Republic of France, and a resident of Paterson, county of Passaic, 5 and State of New Jersey, have invented a new and useful Improvement in Steam-Turbines, of which the following is a specification, the principle of the invention being herein explained and the best mode in which 10 I have contemplated applying that principle, so as to distinguish it from other inventions.

The present invention, relating as indicated to improvements in turbines, has more 15 particular regard to the construction of steam turbines of the kind shown in Letters Patent No. 924,309, granted to me June 8, 1909. As in said patented turbine, the steam is designed to pass from one chamber 20 to another through cylindrical, or rather annular, passages which increase in size progressively from the point of admission of the steam to where it escapes from the machine.

25 One of the principal objects of the present invention is the provision of means for reversibly operating a turbine of the kind in hand.

A further object is to simplify the construction and assembly of the machine so 30 that its manufacturing cost may be decreased, and so that there will be less likelihood of any derangement of the parts, while at the same time the machine is made 35 as small and compact as possible, so as to require a minimum of space for the production of a maximum of power.

The invention further comprehends improvements in various details, both in the 40 turbine proper, in the connections for preventing the escape of steam, and in the bearings for supporting the rotating parts.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—Figure 1 is 55 an axial vertical section of a part of a steam turbine embodying my present improve-

ments; Fig. 2 is a corresponding section showing the remainder of the same turbine, these two figures complementing each other; Fig. 3 is a composite view showing various 60 segmental sections of the turbine, all taken in a transverse vertical plane, as indicated by the section lines on said figure and on Figs. 1 and 2; Figs. 4, 5, 6 and 7 are transverse sectional views of the bearings for 65 supporting the several rotating parts of the turbine, the planes of the various sections appearing in these figures being indicated by the lines 4—4, 5—5, 6—6 and 7—7, Figs. 1 and 2; Fig. 8 is a developed section 70 of a portion of the bearing appearing in Fig. 4, as indicated by the circular section line 8—8 in said Fig. 4; Fig. 9 is similarly a developed section of a portion of the bearing appearing in Fig. 6, as indicated by the circular section line 9—9 in said figure; Figs. 10 and 11 are sectional details of the clutch mechanism whereby the direction of rotation of the turbine may be changed from 75 left to right, or right to left, as desired, 80 the planes of these sections being indicated by the lines 10—10 and 11—11, Fig. 1; Fig. 12 is a side elevational view of a portion of such clutch mechanism for changing the direction of rotation, as viewed from the 85 left in Fig. 11; Figs. 13, 14 and 15 are sectional views of details of the clutch mechanism for holding stationary one or the other of the rotary parts of the turbine, the sections of said figures being indicated 90 by the lines 13—13, 14—14 and 15—15 in Fig. 2; and Figs. 16, 17 and 18 are sectional details of the teeth of such clutch mechanism as indicated by section lines 16—16, 17—17 and 18—18 in Figs. 15, 14 and 13, 95 respectively.

The central shaft 1 of the turbine, shown in Figs. 1 and 2 as extending horizontally through the machine, is supported at its respective ends in bearings 2 and 3 carried by 100 frames 4 and 5, which may be of any suitable construction rising from a base 6. The detailed construction of these bearings will be set forth later. Supported upon the same base 6, and inclosing the rotary parts of the turbine, is a cylindrical casing 7, the ends or heads 8, 8, of which have substantially steam-tight connection with the adjacent rotary parts and are respectively provided with steam supply connections 9; while the drum or cylindrical portion of said casing is connected with an ex- 105 110

haust opening 10, as will be readily understood. The rotary parts, or rotors as they may be properly termed, are two in number. One, the exterior rotor as I shall term it, is built up of a series of disks 11 connected by cylindrical portions 12 so as to form a cylindrical structure within the cylindrical shell or casing, the end disks of such exterior rotor having tubular prolongations 13, 13 surrounding the central shaft 1 of the turbine and journaled in independent bearings 14 supported in the same frames 4 and 5 that support the bearings 2 and 3 for said shaft. The several portions of this rotor are rigidly bolted together so as to make of the same a unitary structure, and it may be regarded as a drum having spaced inwardly directed disks. The other, or interior, rotor is likewise built up of a series of disks 15 which extend radially outward between the disks 11 of the exterior rotor, the disks being carried by drum-like sections 16 held together by bolts 17, and non-rotatably secured to the central shaft of the turbine by keys 18. Said sections of the interior rotor, and thus such rotor in its entirety, are further held against endwise movement on the shaft 1 by locking rings or collars 19, as will be readily understood.

The location of the several disks of the exterior and interior rotor longitudinally of the axis of the turbine is such that the successive annular spaces or expansion chambers A, B, C, D and E formed between the opposing faces of said disks gradually increase from either end of the turbine to the center, it being observed that the right and left halves of the turbine proper are substantial duplicates of each other, and corresponding designating characters are hence applied to the corresponding parts appearing in such two halves.

Attached to the opposed disk-faces of the interior and exterior rotor alternately are series of blades 20 and 21, respectively, the size and form of such blades differing in the several annular spaces, but as these features, as well as the preferred arrangement of the blades, are fully shown by Figs. 1 and 2, taken in conjunction with the several sections appearing in Fig. 3, it is deemed unnecessary to give any detailed description of said blades. The general shape of the individual blades there shown, it may be added, is that of the blade described and claimed in U. S. Patent No. 1,027,309, granted to me May 29, 1912, and the method of attaching said blades to the rotor disks described in said patent may be advantageously employed in the present construction of turbine. It is not meant to imply by the foregoing, however, that other forms of blades, or methods of mounting the same, may not be employed with en-

tirely satisfactory results. The number of series of blades 20 and 21, moreover, while only four in the first expansion chamber A, is five in each of the succeeding chambers B, C, D and E.

The steam, or equivalent pressure fluid, for operating the turbine is admitted at each end of the turbine through the supply connections 9 into an annular steam chest 24 formed in the corresponding head 8 of the casing 7. This steam chest communicates through a series of openings 25 with the inner portion of the first (A) of the annular spaces formed between the opposing faces of the rotor disks. Thence the steam passes through such space to a chamber F connecting the first of such annular spaces with the second, the steam being guided in its passage through such first space by the blades 20 on the one rotor disk so as to react against those 21 on the other, and thus cause rotation of the particular rotor which is free to rotate, it being understood that one or the other of the rotors will be held stationary, and thus in effect be a stator, as will be presently explained. Passing into the second annular space B between the rotor disks, the steam is permitted to still further expand by reason of the increased cross-sectional area of this space, and in its passage through this space it is guided by the blades on the one rotor so as to react against the blades of the other, as in the preceding space, or expansion chamber. An annular chamber C, connects the inner portion or edge of this second space B with the third space C through which the steam now passes radially outward to a third connecting chamber H; thence it returns radially inward through the fourth chamber D to a connecting chamber I, and finally it passes radially outward through the fifth annular space E into the last or fifth chamber J, which opens into the annular space K between the exterior rotor and the surrounding drum or casing 7 of the turbine, which, as previously explained, is in communication with the exhaust.

The mechanism for securing one or the other of the rotors against rotation as desired, thus constituting of the same in effect a stator, comprises simply a shiftable clutch member 26 located between the two bearings 3 and 14, at the left of the turbine, in which are journaled the ends of the central shaft 1 carrying the interior rotor and the corresponding hollow extension or outer tubular shaft 18 carrying the exterior rotor; the teeth 27 on said clutch member are adapted to engage with complementary teeth 28 and 29 on either of two collars 30 and 31 carried by said shaft ends respectively, said member 26 being slidable only in a direction longitudinal of the common axis of said shafts, so that the particular 130

shaft, the collar of which is engaged by said member, will be held against rotation, as will be obvious. Any suitable lever or a feed screw, as shown, may be provided for shifting said clutch member. At the opposite end of the turbine the inner or central shaft 2, which carries the interior rotor, and the tubular shaft 13 surrounding the same, which carries the exterior rotor, terminate in closely adjacent vertical planes and are respectively provided with exterior lugs or teeth 32 and 33, similar to gear teeth, such teeth forming part of the clutch mechanism for connecting either of said shafts as desired with the driving shaft 34, by means of which power is communicated from the turbine to any machinery which it is desired to operate. The abutting end of such driving shaft 34 is provided with lugs or teeth 35 similar to the clutch teeth on such first-named shafts, and a sleeve 36 with interior teeth 37 is mounted in slidable engagement with the teeth on said driving shaft. Said sleeve also has interior teeth 38 at its other end adapted to engage with the teeth 32 or 33 on either of the two shafts 1 or 13, depending upon the location of said sleeve longitudinally of the common axis of said shafts, it being understood that the sleeve remains at all times in engagement with the driving shaft 34. Adjustment of the sleeve 36 to engage with the inner or outer shaft of the turbine is secured by means of an operating slide 39 that is movable longitudinally of the axis of the shafts, and is provided with vertical standards 40 rising on either side of the sleeve and engaging an annular rib 41 thereon, rollers 42 on said standards reducing the friction of the engagement, (see Figs. 11 and 12.) The slide will be operated by a suitable lever, or a feed screw, as shown, as will be readily understood.

It will be evident from the foregoing description of the construction of the clutch mechanism at the respective ends of the turbine, that by rendering stationary one or the other of the two rotors and connecting the driving shaft 34 with that rotor which is left free, such driving shaft may be rotated in either direction as desired, thus rendering the turbine strictly reversible. Such reversal, moreover, may be very quickly effected by a simple shifting of the two clutch members at the respective ends of the turbine, which shifting may be effected simultaneously by a suitable arrangement of connecting gear.

In order to obviate the necessity of packing the joint between the end disks of the exterior rotor and the stationary outer casing of the turbine, and the joint between such end disk of the outer rotor and the adjacent disk of the inner rotor, as also between the latter and such outer casing, I

provide a series of annular dead air spaces between the opposing faces of the disk and end wall of the casing or the two disks as the case may be, three sets of such chambers being provided at each end of the turbine. These chambers are formed by a series of circular grooves 43 and complementary tongues 44, which engage with each other, as clearly shown in Figs. 1 and 2, although not so tightly as to produce any perceptible friction. Escape of steam through such passages, however, is practically impossible, and the little that does escape, in the case of the outer series of spaces, escapes directly into the exhaust chamber of the turbine K, while the inner series of such spaces are likewise connected with this same exhaust chamber by means of radial pipes 45, as shown, leading from near the axis of the turbine to the chamber in question.

It remains to describe the details of the bearings for the rotor shafts, and particularly the special means provided for lubricating said bearings. As shown in Figs. 1, 2, and 4 to 9, inclusive, each of the aforesaid bearings includes a sleeve or bushing 46 in which the corresponding shaft is directly journaled, said bushing having a series of spirally disposed grooves and slots 47, whereby oil received at a suitable point on the exterior of the bushing will be distributed entirely around the bearing. Such oil is designed to be supplied under pressure by pipes or ducts 48, the excess which escapes being collected by other ducts 49 leading from the upper side of the respective bearings. An oil-tight joint is formed between the ends of the respective bushings 46 and the corresponding shafts by means of stepped collars, or flanges 50, fixedly secured on said shafts and snugly abutting against the said bushings. In the case of the bearing 2 at the right-hand end of the turbine, as illustrated in Fig. 1, the bushing 46 for the central shaft of the rotor is supported within the outer shaft 13, which in turn is journaled in a second bushing 46 suitably held in the adjacent portion of the frame. The oil for the inner bearing, that of the central shaft in inner bushing 46, is admitted to the grooves and slots 47 in said bushing through other slots, or rather apertures 51, in the outer, tubular shaft 13, as is best shown by Figs. 6 and 9.

The general operation of the foregoing described mechanism, constituting my improved turbine, should be readily apparent from the description already given of its several component parts. The course of the steam, which is simultaneously admitted under relatively high pressure at both ends of the machine, follows the series of annular expansion chambers A, B, C, D and E, with their connecting chambers F, G, H and I, finally passing into the chamber J, from

which it escapes, reduced to its minimum pressure, into the exhaust chamber K formed between the shell of the exterior rotor and the outer casing of the machine. 5 Each successive expansion chamber, it will be observed, is of increased size or cross-sectional area, being properly proportioned in the design of the turbine to the increase in volume that accompanies the decrease in 10 pressure of the steam, or other pressure fluid, wherewith the machine is being operated. Depending upon the disposition of the holding-clutch member 26, either the interior or exterior rotor will be caused to 15 rotate by the force of the steam reacting on the series of blades in the several annular expansion chambers between the rotor-disks, the one rotating when thus free to operate, in one direction, while the other will turn 20 in the opposite direction when the clutch member is shifted. The clutch at the other, or driving end of the turbine, will of course be shifted to connect the driving shaft with whichever rotor is being operated. Aside 25 from the readiness with which my improved turbine may be thus reversed in direction, it will be seen to be simple of construction, the several parts being readily assembled together and forming, in the assembled condition of parts, a compact, solid and powerful motor in very small compass.

Other modes of applying the principles of my invention may be employed instead of the one explained, change being made as 30 regards the mechanism herein disclosed, provided the means stated by any of the following claims or the equivalent of such stated means be employed.

I therefore particularly point out and distinctly claim as my invention:—

40 1. In a turbine, the combination of a central shaft; spaced outwardly directed disks carried by said shaft and constituting an interior rotor; an exterior rotor surrounding said shaft and carrying inwardly directed disks alternating with the disks of said interior rotor, the spaces between the opposing disk-faces of said interior and exterior rotors successively increasing in size 45 from the intake to exhaust; alternating series of blades carried by such opposing disk-faces; means located at one end for retaining either of said rotors against rotation, as desired; a driving shaft at the other end; 50 and means for connecting either of said rotors with said driving shaft, as desired.

55 2. In a turbine, the combination of a central shaft; spaced outwardly directed disks carried by said shaft and constituting an interior rotor; an exterior rotor surrounding said shaft and carrying inwardly directed disks alternating with the disks of said interior rotor, the spaces between the opposing disk-faces of said interior and exterior rotors successively increasing in size 60

from the respective ends of the turbine to a central transverse plane; connections for supplying pressure-fluid to the end spaces and for exhausting the same from the central spaces; alternating series of blades carried by such opposing disk-faces; and means for retaining either of said rotors against rotation, as desired. 70

3. In a turbine, the combination of a central shaft; spaced outwardly directed disks carried by said shaft and constituting an interior rotor; an exterior rotor surrounding said shaft and carrying inwardly directed disks alternating with the disks of said interior rotor, said exterior rotor being formed 75 with tubular extensions at each end rotatably mounted on said shaft; alternating series of blades carried by the opposing disk-faces of said interior and exterior rotors; a driving shaft; means adapted to connect 80 either one end of said central shaft or corresponding tubular extension of said exterior rotor with said driving shaft, as desired; and other means adapted to retain either of said rotors against rotation, as 85 desired.

4. In a turbine, the combination of a central shaft; spaced outwardly directed disks carried by said shaft and constituting an interior rotor; an exterior rotor comprising 90 a drum having tubular end extensions rotatably mounted on said shaft and carrying inwardly directed disks alternating with the disks of said interior rotor; alternating series of blades carried by the opposing faces 95 of said interior and exterior rotors; a driving shaft aligned with one end of said central shaft, a suitable clutch member adapted to connect either such end of said central shaft, or the corresponding end extension 100 of said exterior rotor with said driving shaft, as desired; and another shiftable clutch member adapted to engage the other end of said central shaft, or the corresponding end extension 105 of said exterior rotor with said driving shaft, as desired; and retain the same against rotation.

5. In a turbine; the combination of a central shaft; spaced, outwardly directed disks carried by said shaft and constituting an interior rotor; an exterior rotor comprising 115 a drum having tubular end extensions rotatably mounted on said shaft and carrying inwardly directed disks alternating with the disks of said interior rotor; alternating series of blades carried by the opposing faces 120 of said interior and exterior rotors; spaced bearings at one end of the turbine, respectively supporting one end of said shaft and the corresponding end extension of said exterior rotor; and a shiftable clutch member 125 between said bearings adapted to engage said shaft or end-extension, as desired, and retain the same against rotation.

6. In a turbine; the combination of a central shaft; spaced, outwardly directed disks 130

carried by said shaft and constituting an interior rotor; an exterior rotor comprising a drum having tubular end extensions rotatably mounted on said shaft and carrying 5 inwardly directed disks alternating with the disks of said interior rotor; alternating series of blades carried by the opposing faces of said interior and exterior rotors; spaced bearings at one end of the turbine, respectively supporting one end of said shaft and the corresponding end extension of said exterior rotor; a shiftable clutch member between said bearings adapted to engage said shaft or end-extension, as desired, and retain the same against rotation; a bearing 10 supporting the other end-extension of said

exterior rotor; a bearing supporting the corresponding end of said shaft within said last-named end-extension; a driving shaft aligned with the end of the aforesaid shaft 20 thus supported in said last-named end-extension; and a shiftable clutch adapted to connect said driving shaft and either said end-extension or corresponding shaft end supported therein. 25

Signed by me, this 18th day of January, 1913.

ALFRED BONOM.
